The ornamental design for a grip set for a video game controller, as shown and described.

DESCRIPTION

FIG. 1 is a top perspective view of a grip set for a video game controller showing a left grip and right grip of our design;

FIG. 2 is a bottom perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a left side elevational view of the left grip of a video game controller;

FIG. 8 is a right side elevational view of the left grip of a video game controller;

FIG. 9 is a left side elevational view of the right grip of a video game controller; and,

FIG. 10 is a right side elevational view of the right grip of a video game controller.

The broken lines indicate unclaimed portions and form no part of the claimed design.

FIGS. 7-10 shows the left and right grips of a video game controller separately for clarity.
